UNITED STATES PATENT OFFICE.

JOHN GRIBBEL, OF WYNCOTE, PENNSYLVANIA.

COIN-CONTROLLED GASOMETER.

SPECIFICATION forming part of Letters Patent No. 650,506, dated May 29, 1900.

Application filed February 13, 1900. Serial No. 5,038. (No model.)

To all whom it may concern:

Be it known that I, JOHN GRIBBEL, a citizen of the United States, residing at Wyncote, in the State of Pennsylvania, have invented 5 certain new and useful Improvements in Pre-payment Mechanism, of which the following is a specification.

My invention relates generally to apparatus designed to contain or control a supply of 10 vendible material, and arranged, upon the deposit upon or in adjacency to certain parts of its mechanism, of a coin of predetermined dimensions, to permit the delivery or release of a given quantity thereof,—and relates especially to apparatus of the foregoing character 15 when constructed to operate in connection with fluids such as gas.

My present improvements relate to the valve controlling mechanism of prepayment 20 gas motors, and especially to a particular type of such mechanism set forth and illustrated in Letters Patent No. 569,147, granted October 6th, 1896, upon the application of John Delaney, reference to which patent is 25 to be had for a more thorough understanding of the art.

In the accompanying drawings I show, and herein I describe, a good form of a convenient embodiment of my invention, the particular subject matter claimed as novel being hereinafter definitely specified.

In the drawings, Figure 1 is a top plan view of a meter equipped with my improvements, the top or cover of the meter being supposed 35 removed to exhibit the arrangement of the mechanism in the interior of the same.

Figure 2 is a view in side elevation of the valve controlling mechanism to which my improvements especially relate.

Figure 3 is a view in perspective of the following gear and associated parts.

Figure 4 is a view in end elevation of the parts shown in Figure 2, the pinion bar being in section on the dotted line 4—4 of said 45 Figure 2.

Figure 5 is a transverse section of the parts shown in Figure 2, section being supposed on the dotted line 5—5, in said figure, the following gear being supposed brought to a position to be on said dotted line. Similar figures of reference indicate corresponding parts.

In the accompanying drawings, A, Figure

1, indicates the casing of a gas meter of any usual form, provided with the inlet pipe or opening *a* and the outlet opening *a'*. 55

*a*² is a valve casing mounted within the interior of the meter casing, into which the inlet pipe *a* discharges and from which the gas passes to the measuring contrivances, of usual construction, in the body of the meter casing, 60 the arrangement being such that all gas passing through the meter, as a whole, passes first through said valve casing and through a valve port disposed within the same.

A valve *a*³ of any preferred construction, 65 mounted in the valve casing, controls said valve port. Said valve is provided with a valve stem *B*, connected to which is a slotted rock arm *b*. The arrangement of the stem and rock arm, with relation to the valve, is 70 such that when the body of said arm is in a horizontal position, the valve is open and the gas is free to enter and pass through the body of the meter, while when said arm is depressed, the valve is forced to its seat and the 75 inflow of gas from the valve casing to the meter is stopped.

C, Figure 1, is a valve plate upwardly from which extends the spindle *C'*, operated to rotation by the link arms *C*², *C*³, the outer extremities of which are connected to rocking studs *C*⁴, *C*⁵, connected with the diaphragms, or operative parts, in the interior of the meter in the usual manner. The inner extremities of said link arms are united to a crank 80 or arm *C*⁶, connected with said spindle *C'*, and rotatable about it. A worm mounted upon said spindle *C'*, engages in a worm wheel *D* on the main arbor *D'* of the dial mechanism, and, in the operation of the meter occasions the rotation of said arbor. The outer extremity of said arbor is operatively connected in the usual manner with a dial hand adapted to register the total of gas consumed regardless of the operation of the special mechanism hereinafter described, said dial itself and said hand (not shown) being contained within and protected by the usual dial casing *B*. 85

E is a screw threaded shaft, shown particularly in Figure 2, mounted free for rotation, but held against longitudinal movement, in a pair of supporting plates *E'*, *E*², erected and secured in any desired manner in the upper 90 95 100

portion of the meter,—said shaft being provided with a prolongation, E^3 , as shown,—which extends through the meter casing to the interior of the lock casing (omitted from

5 Figure 2, but shown in Figure 1) where it is equipped with a driven pinion E^4 .

6 e are a pair of guide rods connective of the upper portions of the supporting plates E^1 , E^2 .

10 F is what I term the follower gear wheel, provided with a threaded bore, and mounted upon and in threaded engagement with the shaft E . A hub f of said wheel is provided with a circumferential recess f' .

15 G is what I term the follower yoke, of breadth equal to that of the recess f' , the under face of which embodies a recess of radius corresponding to that of the base of the recess f' , which yoke is seated in said recess 20 as a saddle, so to speak, in such position that its respective ends extend beneath the respective rods e , e , as shown more particularly in Figure 3.

25 The rods e , e , therefore, maintain said yoke in a horizontal position notwithstanding the rotation of the gear which carries it.

30 Manifestly as the follower gear F rotates it will travel along the shaft, carrying with it the yoke G , said yoke, of course, participating freely and without binding in the longitudinal movement of the follower gear, but not participating in its rotative movement.

35 H is what I term a pinion bar, or elongated pinion, supported, in parallelism with the shaft E , in such position that its teeth are normally in registry with the teeth of the follower gear, a pinion h permanently mounted on the distant end of said pinion, being in constant mesh with a worm D^2 , carried by the 40 main arbor D' .

45 A finger g on the end of the follower yoke is engaged in the slot of the rock arm b . The other end of the yoke carries a horizontally disposed rack i , engaged with a gear j , mounted upon the inner end of an arbor, J , the outer end of which projects to the exterior of the main casing A and terminates within a dial box K .

50 The end of said arbor J is assumed to be provided with a hand adapted to travel across a graduated dial plate contained within the dial box K .

55 M is a leaf, or buffer, spring, arranged beneath what I term the exhaust end of the screw shaft E , for a purpose hereinafter set forth. Conveniently said spring is mounted upon a brace rod m affixed at its respective extremities to the basal portions of the respective plates E^1 , E^2 .

60 N , Figure 2, is a stop bar projecting from the follower yoke and adapted to register with, and in some positions of the yoke extend through, a corresponding opening formed in the plate E' .

65 P , Figure 4, is a stop arm mounted upon the distant end, as I term it, of the screw shaft E , and revolving with it, and adapted, when

the follower gear and yoke have traveled so close to the plate E' that the stop bar N projects through its opening therein—to encounter said projecting bar N .

70 The projection of the bar N in the path of the stop arm, of course, prevents further rotation of the shaft E in the direction which occasions the travel of the follower gear toward the plate E' , and thus limits the outward movement of the follower gear and yoke, occasioned by the rotation of the shaft E .

75 Q is a coin lock casing, mounted upon the exterior of the meter casing, as shown in Figure 1, and provided with the usual coin slot, q , and operating handle Q' .

80 The coin lock mechanism *per se* forms no part of the present invention, and any suitable devices operative for the purpose may be employed; suffice to say, that upon the insertion of a coin of predetermined value within the slot, said coin operates to temporarily fix in given relation the parts of the lock, so that rotation imparted to the handle Q' , occasions the rotation of a gear wheel connected with the inner portions of the lock which gear is directly or through intermediate wheels in mesh with the gear E^4 , shown in Figure 2.

85 The normal position of the parts may be assumed to be that in which the gear F is at the exhaust end of the screw shaft E , with the pin or finger g carried by the follower yoke engaged in the curved end of the slot of the rock arm b , maintaining said arm in its 90 deflected position and consequently the valve port in the valve casing a^2 closed.

95 When, then, a coin is inserted as described and the handle Q' rotated, the gear E^4 and the screw shaft E are caused to rotate in consonance therewith. The rotation of the screw shaft occasions the travel of the gear and yoke toward the distant end of the screw shaft a distance corresponding to the rotation imparted to the rotating handle. In such rotation of the screw shaft the gear is held against rotation by its engagement with the teeth of the pinion bar, its teeth sliding along the teeth of said bar,—the bar itself is of course held against rotation, when the screw shaft E is rotated, by its engagement with the worm D^2 .

100 The finger g of the yoke in such travel passes along the straight part of the slot of the rock arm b , forcing said arm into horizontal position, with the result that the valve in the valve casing a^2 is thrown and maintained open. Incidentally, also, the dial hand on the spindle J , will be set to a position indicating the distance the follower gear, must travel to reach the exhaust end of the shaft E , stated, for the 105 benefit or information of the consumer, in terms expressing the amount of gas paid for and to be delivered before another payment is necessary.

110 The valve in the valve casing a^2 being open, 115 gas is free to pass through the meter for consumption, and in so passing occasions the operation of the main arbor D' , and consequently of the pinion bar and the gear F . The rota-

tion of said gear causes its travel along the for the time being non-rotating shaft E and toward its exhaust end.

As the gear F reaches a given point in proximity to said exhaust end, the finger *g* enters the curved end of the slot in the arm *b* and deflects said arm to the position in which the valve *a*³ in the casing *a*² is closed. Incidentally in such travel of the yoke F the rack *i* causes the rotation of the wheel *j* and spindle *J*, and of course a corresponding movement of the dial hand in the dial box K.

When the gear F and yoke G have reached a point in proximity to the exhaust end of the screw shaft E, the valve in the valve casing *a*² will be brought to closed position.

It has frequently happened, however, in the use of apparatus of this kind, that by reason of the valve not being seated tightly upon its seat in the casing *a*², gas from the inlet pipe continues to pass in small quantities into the meter and from time to time to occasion movements of the mechanism thereof, and consequently the further rotation of the pinion bar H and gear F, with the result, said parts being positive in their engagements, that,—after the gear F has made contact with the plate E² and is unable to travel farther longitudinally of the shaft E,—one or the other of the parts has under the strain broken so that the meter has become useless.

In my improved construction I taper the inner end of the pinion bar conveniently in the manner shown in the drawings, with the result that, when the follower gear comes to such position at the exhaust end of the screw shaft and near to the plate E², that the valve in the valve casing *a*² will in the normal operation of the parts be closed by the throw of the rock arm *b* by the finger *g*, the teeth of said follower gear are close to the reduced end portion of the pinion bar H. Thereupon, in any further action of the moving parts of the meter, due to the fact that the valve *a*³ has not closed tightly at the proper time, with the result that the gas continues to pass through it,—rotation of the pinion bar H, occasioning rotation of the gear F and consequent longitudinal travel of said gear, will carry said gear quite close to the plate E² and opposite to the reduced end of the pinion bar H and out of engagement with the teeth of the latter; consequently any further rotation of said pinion bar will be idle and not accompanied by jamming or breakage of the parts.

The tapered ends of the teeth of the pinion bar H are slightly inclined or beveled, as shown in Figure 1, so that after the follower gear F has passed to a position opposite to the reduced end of the said pinion and out of engagement with said teeth, said gear will, when the rotatable handle Q' is turned and said gear begins to travel back to the distant point of the screw E, if its teeth are not in alinement with the spaces between the teeth of the pinion bar, encounter as to its teeth, the beveled ends of the teeth of the pinion

bar and be thereby guided into registry or mesh with the teeth of the pinion bar.

The stop bar N and stop plate P of course prevent the follower gear and yoke from being carried by the rotation of the handle Q' more than a fixed distance away from the exhaust end of the screw E.

The follower-gear, in the normal operation of the parts in which the valve *a*³ closes its port tightly at the proper time, does not travel close enough to the plate E² to carry its teeth out of engagement with the teeth of the pinion bar. When, however, owing to failure of the valve to close tightly, the pinion bar continues to revolve and the gear is carried out of engagement with the teeth of the said pinion bar, the periphery of said gear bears against the buffer spring M, slightly depressing it, and said spring bearing against said gear holds said gear against rotation. Were it not for said spring, the gear, after it has passed out of engagement with the pinion bar, would, when the wheel E⁴ and shaft E are rotated to carry the gear to the distant end of the shaft E,—simply rotate idly with the shaft, remaining in the same position with respect to the plate E². The spring holds the gear against rotating with the shaft E, when said gear is out of engagement with the teeth of the bar H,—and consequently when the shaft E is rotated the gear is caused to travel back into engagement with the pinion bar.

Having thus described my invention, I claim and desire to secure by Letters Patent—

1. In a coin controlled sale and delivery apparatus for fluids, devices adapted to enable the withdrawal of the fluid in predetermined quantity, a valve controlling the flow of the fluid, valve closing mechanism automatically operated by the passage of the fluid, including a pinion bar and a gear in mesh with said pinion bar and adapted to rotate in unison with it and to travel along it, said bar being provided with a reduced area which is reached by the gear in its travel if the valve closing movement is ineffective, substantially as set forth.

2. In a coin controlled sale and delivery apparatus for fluids, devices adapted to enable the withdrawal of fluids in prearranged quantity, mechanism automatically operated by the passage of the fluid to close the apparatus against the exit of more than the pre-arranged quantity, including two members, which when the fluid continues to flow after the closing movement of the parts become automatically disengaged, substantially as set forth.

3. In a coin controlled sale and delivery mechanism for fluids, in combination, a screw shaft, a follower gear mounted on said shaft, a guide mounted in parallelism with said shaft, a follower yoke structurally independent of the gear but mounted as a saddle on said gear, and also structurally independent of the guiding device, but guided by said

- guiding device, a pinion bar in mesh with said follower gear, mechanism connective of said pinion bar and a moving part of the sale and delivery mechanism, a valve controlling arm and a connection between said follower yoke and said arm, substantially as set forth.
4. In a coin controlled sale and delivery mechanism for fluids, in combination, a screw shaft, a follower gear mounted on said shaft and having a circumferential recess, a pair of guide bars mounted in parallelism with said shaft, a follower yoke, the body of which rests in the recess of the said follower gear, and the extremities of which extend beneath the respective guide bars, an elongated pinion bar in mesh with said follower gear, mechanism connective of said pinion bar and a moving part of the meter, a valve controlling arm and a connection between said follower yoke and said arm, substantially as set forth.
5. In a coin controlled sale and delivery mechanism for fluids, in combination, a screw shaft, a follower gear mounted on said shaft and having a hub embodying a circumferential recess, a pair of guide bars mounted in parallelism with said shaft, a follower yoke carried in the recess of the hub of the follower gear, a pinion bar in mesh with said follower gear, mechanism connective of said pinion bar and a moving part of the meter, a slotted valve controlling arm, and a finger carried by the follower yoke engaged in the slot of said arm, substantially as set forth.
6. In a coin controlled sale and delivery mechanism for fluids, in combination, a screw shaft, a follower gear mounted on said shaft, and having a laterally extending hub, guide bars mounted in parallelism with said shaft, a follower yoke structurally independent of the follower gear but mounted as a saddle on the hub of said gear, said yoke and hub being held in operative relation by means of a transversely extending groove or recess formed in one into which recess the other projects, said follower yoke being also structurally independent of the guide bars but extending transversely past them, a pinion bar in mesh with said follower gear, mechanism connective of said pinion bar and a moving part of the sale and delivery mechanism, a valve controlling arm, and a connection between said follower yoke and said arm, substantially as set forth.
7. In a coin controlled sale and delivery mechanism for fluids, in combination, a meter, a valve and valve controlling devices, including a screw shaft, a follower gear and yoke mounted upon and adapted to have longitudinal movement with relation to said screw shaft, means for manually occasioning the movement of said follower gear and yoke in one direction along said shaft, mechanism connective of a moving part of the meter and said follower gear and yoke to occasion their movement in the opposite direction, one of the parts or members of the apparatus in gear or mesh with another, being so arranged as to

pass out of engagement with the teeth of the member with which it is in mesh with the follower and gear reach a point near the exhaust end of the shaft, substantially as set forth. 70

8. In a coin controlled sale and delivery mechanism for fluids, in combination, a screw shaft, a follower gear, a follower yoke, and a pinion bar in mesh with said gear and having at one end teeth of diminished height, substantially as set forth. 75

9. In a coin controlled sale and delivery mechanism for fluids, in combination, supporting plates, a screw shaft, a follower gear, a follower yoke, a pinion bar having a reduced end of tapered outline, means for rotating the pinion bar, and means for rotating the screw shaft, substantially as set forth. 80

10. In a coin controlled sale and delivery mechanism for fluids, in combination, a screw shaft, a follower gear, a follower yoke, a pinion bar having a reduced end of tapered outline, the teeth of which at their reduced ends have inclined faces, means for rotating the pinion bar, and means for rotating the screw shaft, substantially as set forth. 85

11. In a coin controlled sale and delivery mechanism for fluids, in combination, a screw shaft, a follower gear, a follower yoke, a pinion bar having teeth of diminishing height at one end, a buffer spring arranged in adjacency to the diminished portions of the teeth of the pinion bar and adapted to bear against the follower gear, substantially as set forth. 90

12. In combination, the meter having an inlet controlled by a valve, a valve arm connected to said valve, a pinion bar rotated by the operation of the ordinary moving parts of the meter and having an end or portion of reduced diameter, a screw shaft, a follower gear on said shaft and normally engaged with said pinion bar, a follower yoke engaged with the valve arm, and means for manually rotating said screw shaft, substantially as set forth. 100

13. In combination, the meter having an inlet controlled by a valve, a valve arm connected to said valve, a pinion bar rotated by the operation of the ordinary moving parts of the meter and having an end or portion of reduced diameter, a screw shaft, a follower gear on said shaft and normally engaged with said pinion bar, a follower yoke engaged with the valve arm, and a buffer spring in the vicinity of the reduced diameter of the pinion bar, substantially as set forth. 110

14. In a prepayment sale and delivery apparatus, in combination with the screw shaft, follower gear and follower yoke, the pinion bar having a reduced portion, and the buffer spring, substantially as set forth. 115

In testimony that I claim the foregoing as my invention I have hereunto signed my name this 3d day of February, A. D. 1900.

JOHN GRIBBEL.

In presence of--

F. NORMAN DIXON,
THOS. K. LANCASTER.
